UNITED STATES PATENT OFFICE.

FRANK A. HALL, JR., OF MONTCLAIR, NEW JERSEY.

SPRING-FRAME.

SPECIFICATION forming part of Letters Patent No. 729,334, dated May 26, 1903.

Application filed September 9, 1902. Serial No. 122,783. (No model.)

To all whom it may concern:

Be it known that I, FRANK A. HALL, Jr., a citizen of the United States, and a resident of Montclair, in the county of Essex and State 5 of New Jersey, have invented new and useful Improvements in Spring-Frames, of which the following is a full, clear, and exact description.

This invention relates to a frame for the woven-wire springs used in bed construction.

10 The object of the invention is to render these frames thoroughly rigid. Heretofore it has often been a disadvantage that the frames are particularly liable to rupture, slight strains being sufficient in some cases to make 15 the frame quite useless. This weakness is mainly present in the connection between the side bars and the brackets, and my invention resides in forming on these parts peculiar interengaging wedge-like surfaces which are 20 bound firmly together, thus to prevent any twisting or working movements of the parts.

This specification is a specific description of one form of my invention, while the claims are definitions of the scope thereof.

25 Reference is to be had to the accompanying drawings, forming a part of this specification, in which similar characters of reference indicate corresponding parts in all the figures.

Figure 1 is a side elevation of the invention, 30 and Fig. 2 is a section on the line 55 of Fig. 1. *f* indicates the bracket, which has an arm *f'* to engage the bed-frame and support the spring-frame thereon.

g indicates the end rail, and *h* the spring. 35 *i* indicates the side rail of the spring-frame, and *k* a bolt which extends through the end of the side rail and into the bracket and through the end rail, thus clamping these parts *i*, *f*, and *g* together. Formed in the 40 side rail *i* is an opening *i'*, which serves to receive the bolt *k* and also to receive the tapered stud *f'*, which is formed on and projected downward from the bottom of the bracket *f*. This stud being tapered is forced by the pressure 45 of the bolt *k* into one end of the opening *i'*, and thus the before-mentioned wedge-like en-

gaging surfaces are provided. This construction operates to prevent wrenching and twisting the parts of the frame, thereby holding said frame rigid in every respect. 50

Various changes in the form, proportions, and minor details of my invention may be resorted to without departing from the spirit and scope thereof. Hence I consider myself entitled to all such variations as may lie 55 within the scope of my claims.

Having thus described my invention, I claim as new and desire to secure by Letters Patent—

1. A spring-frame for beds comprising a 60 side rail having an opening in its side, a bracket having a tapered stud projecting downward from the bracket transversely of the side rail into the opening thereof, said bracket also having a projected arm capable 65 of engaging the bed to sustain the spring-frame thereon, and a bolt engaged with the bracket and side rail and serving to draw the side rail up against the bracket and wedge the tapered stud into the said opening in the side 70 rail.

2. A spring-frame for beds comprising a side rail having an opening in its side, a bracket having a tapered stud projecting downward from the bracket transversely of the side rail into the opening thereof, said bracket also having a projected arm capable 75 of engaging the bed to sustain the spring-frame thereon, an end rail lying on the side of the bracket opposite the side rail and a bolt 80 passed through the end rail, bracket and side rail and serving to draw said parts together and wedge the tapered stud tightly into the said opening in the side rail.

In testimony whereof I have signed my 85 name to this specification in the presence of two subscribing witnesses.

FRANK A. HALL, JR.
